UNITED STATES PATENT OFFICE.

HANS K. LORENTZEN, OF NEW YORK, N. Y.

COIN BOX.

Application filed March 26, 1926. Serial No. 97,535.

This invention relates to a coin box, and has for its object the provision of a box that will minimize losses in the operation of slot machines or other coin-operated machines.

The particular object of the invention is to provide a box that can be quickly inserted into coin-receiving position in a machine, and which upon withdrawal, will be automatically locked so as to prevent removal of coins by the servicing attendant. The attendant merely collects the filled boxes, replacing them with empty boxes, and carries the filled boxes to the central office where they are opened and emptied by the proper responsible official.

While I have disclosed a preferred embodiment of the invention for purposes of illustration, it should be understood that the structure may be modified in various ways without departure from the true spirit and scope of the invention as hereinafter defined and claimed.

In the drawings, Fig. 1 is a plan view, partly broken away, showing the coin box in receiving position in the machine;

Fig. 2 is a longitudinal section through the structure shown in Fig. 1;

Fig. 3 is a fragmentary view similar to Fig. 1 but showing the coin box partly removed from its compartment;

Fig. 4 is a partial section showing the locking mechanism, the coin box being in receiving position in its compartment;

Fig. 5 is a view similar to Fig. 4 showing the box partly removed from its compartment;

Fig. 6 is a side elevation of part of the box in opened position;

Fig. 7 is a plan view of the parts shown in Fig. 6.

The coin box 10 is normally housed in a compartment 11 formed in the slot machine or other device on which the box is to be used. The compartment is provided with a hinged door 12 secured by a suitable lock 13. The upper wall of the coin box has two apertures 14 formed therein in cooperative relation with the coin chutes 15, and of a size just large enough to admit the coin by which the machine is operated. These apertures 14 are controlled by a slide 16 supported in contact with the upper wall of the coin box by suitably formed shoulders 17. The slide is formed with apertures 18

adapted at a certain position of the slide to coincide with apertures 14.

One end of slide 16 pivotally carries an arm 19 connected with the lever 20 which is carried in a control box 21. The control box closely slides into one end of the cash box and carries a pivot pin 22 which rides in a slot 22^a of the lever. The lower end of lever 20 is hinged to the locking plate 23, which slides within the control box 21 and has a horizontal slot 24 formed therein. The slot 24 has lateral extensions 25 adapted to receive the spring-pressed tumblers 26 carried in the control box. The forward end of locking plate 23 is formed with a downwardly opening notch 27. A key lever 28 is pivoted in the control box and has an upward extension fitting into notch 27 and has a lower extension 29 adapted to fit into a notch 30 formed in the key. The locking plate is guided in its movement by a pin 31 carried by the control box and extending into a slot 32 in the locking plate.

A latch member 33, which is pivoted to the control box carries a beveled foot 34 adapted to engage behind a stop 35 formed on the inside of the coin box as shown in Fig. 1. A spring 36 presses the latch member into engagement with the stop. The forward end of the latch member 33 extends beyond the front wall of the control box and ends in a hook 37.

A bracket 38 carrying a key member 39 and a stop 40 is permanently mounted on the rear wall of compartment 11. The forward part of key 39 is so formed that when the key extends into the keyway 41 of the control box (Fig. 4) the tumblers 26 are held out of the slot extensions 25 and in alignment with the horizontal slot 24. At the same time the arm 29 extends into notch 30 formed on the key. Leaf springs 42 are attached to one side of compartment 11 and resiliently hold the box against the opposite side. The stop 40 insures accurate positioning of the coin box in the compartment.

When the coin box is in the position illustrated in Figs. 1, 2 and 4 it will catch any coins falling into chutes 15. When the attendant comes around to service the machine and remove the accumulated coins, he first opens door 12, and then pulls the coin box from the compartment. During the outward movement of the coin box, key lever 28 is rocked by reason of arm 29 being engaged in notch 30 of the key. This move-

ment of lever 28 is transmitted to the locking plate 23 (the tumblers 26 being held in neutral position by the key) and thence through lever 20 and arm 19 to slide 16, 5 moving the slide rearwardly to the position shown in Figs. 3 and 5. When the slide is in this position it partly closes the apertures 14 and prevents removal of the coins through these apertures. In this position the tumblers 26 engage in the slot extensions 25 and prevent movement of the slide. At the same time an extension 43 of the slide engages behind latch 33 and holds it in engagement with stop 35 (Fig. 3) preventing 10 removal of the control box from the coin box.

The attendant now inserts an empty coin box of identical construction with the one just removed into the compartment 11. This 20 empty box also has its slide 16 locked in the protective position of Figs. 3 and 5. As this empty box is shoved home from the position of Fig. 3 to that of Fig. 4 the stationary key 39 will operate the tumblers 36 25 and lever 28, thereby unlocking the slide and moving it to open position.

The attendant is unable to remove coins from the coin boxes, but must take the collected coin boxes to the central office. At the 30 latter place a key 44, identical in configuration with stationary key 39, is inserted in keyway 41, unlocking the tumblers and moving slide 16 to the rear, thereby removing

extension 43 from behind latch 33. The hook 37 formed on the forward end of the latch member is now pushed and held in engagement with an aperture 45 in the key 44, disengaging latch 33 from stop 35 and hooking the control box to key 44. When the latter is pulled to the right it carries 40 with it the control box 21 and slide 16, opening the front end of the coin box (Fig. 6) and permitting ready removal of the coins. The slide and control box are now 45 pushed back into the box and the key withdrawn, leaving the empty box in the condition of the box shown in Fig. 3 and ready for placement in a vending machine.

I claim:—

1. A coin box having an open end, and 50 an aperture in one side, a control box fitting into the open end, and key controlled means for obstructing said aperture and for assisting in locking said control box in position in said coin box.

2. A coin box having an open end, and 60 an aperture in one side, a control box fitting into the open end, a latch normally holding said control box within said coin box, key controlled means for obstructing said aperture and said latch, a key for operating said means, said latch having a part engaging with said key when in unlatched position.

In testimony whereof I affix my signature.

HANS K. LORENTZEN.
